MEANS FOR ACCELERATING THE OPENING OF DRY-PIPE VALVES.

Application filed February 1, 1926. Serial No. 85,235.

In the operation of a dry pipe valve it is a desideratum that the time interval between the opening of a sprinkler head and the tripping of the valve should be reduced

5 as far as possible since when a sprinkler head opens it is important to have the water reach the open head with the least possible delay. For the accomplishment of this general object various devices have been devised, some of which perform the accelerating 10 operation when a sprinkler head gives way by quickly exhausting the air from the system adjacent the dry pipe valve, and others of which perform this accelerating 15 function by introducing pressure into the intermediate chamber of the dry pipe valve. In both instances the result is to speed up the operation of tripping the dry pipe valve so as to allow water to flow into the system. 20 Some of the prior devices for speeding up the operation of the dry pipe valve are so constructed that they will operate when the pressure in the system falls relatively rapidly, as would be the case when a sprinkler 25 head gives way, but will not operate when the pressure in the system falls very slowly as would result from a slow leakage of air in the system.

My present invention relates to a device 30 of this class and has for its object to provide a novel mechanism for speeding up the opening movement of a dry pipe valve which is highly sensitive in that it will operate with a very small fall of pressure and which is 35 also rapid, speedy and accurate in its operation.

The invention may be embodied in a device which will perform its function either 40 by exhausting the air from the dry pipe system, which devices are commonly referred to in the art as "exhausters", or it may be embodied in a device which will perform its function by introducing pressure into the intermediate or neutral chamber 45 of the dry pipe valve, which devices are known in the art as "accelerators."

In order to give an understanding of the 50 invention I have illustrated in the drawings some selected embodiments thereof which will now be described after which the novel features will be pointed out in the appended claims.

Fig. 1 is a view partly in section illustrating 55 a device embodying my invention and operating on the exhauster principle;

Fig. 2 is a section on the line 2—2, Fig. 1;

Fig. 3 is a sectional view showing a device embodying my invention associated with a dry pipe valve and operating as an accelerator.

A device embodying my invention comprises a main valve chamber and a pilot valve chamber, both communicating with the system and normally having the same pressure therein as exists in the system, a main 60 valve in the main valve chamber which controls a port leading from said chamber either to the atmosphere or to the neutral chamber of the dry pipe valve, and a pilot valve in the pilot valve chamber which controls an exhaust port from said pilot valve chamber and means for opening the pilot valve when the pressure in the system decreases. By the use of the pilot valve it is possible to produce a mechanism in which 65 the pilot valve will be very sensitive and will be opened when the pressure in the system is reduced a very small amount. The opening of the pilot valve will immediately cause the opening of the main 70 valve and as a result the accelerating action is performed with almost no delay following the giving way of a sprinkler head.

Referring first to Figs. 1 and 2, the device is embodied in a casing 1 which has 75 within it a main valve chamber 2 which communicates with the system through a pipe (not shown) screwed into the opening 3. This main valve chamber 2 has an exhaust port 4 which is normally closed by a 80 main valve 5, the exhaust port 4 leading either to the atmosphere or to the neutral chamber of a dry pipe valve.

The casing 1 has also within it a pilot valve chamber 6 which is provided with an 85 exhaust port 7 leading to the atmosphere, said port being normally closed by a pilot valve 8. The chambers 2 and 6 are herein shown as separated by a movable partition 9 in the form of a diaphragm which is 90 mounted on the stem 10 of the main valve 5. The pilot chamber 6 also has communication with the system so that normally the same pressure exists in both the chambers 2 and 6 and the diaphragm 9 will be balanced. 100 In the construction herein shown the communication between the pilot valve chamber 6 and the system is through a duct 11 formed in the valve stem 10 and opening at one end into the chamber 2 and at the other end 110 into the chamber 6.

The main valve 5 is also connected,

through the medium of a yoke 22, to another diaphragm 12 which extends across the casing and divides the main valve chamber 2 from the pressure chamber 13. This 5 pressure chamber has communication through a pipe 14 with an auxiliary pressure chamber 15 at the upper end of the casing, which chamber is separated from the chamber 6 by another diaphragm 16.

- 10 The chambers 6 and 15 communicate with each other through a restricted orifice so that normally when the main and pilot valves 5 and 8 are closed the system pressure will exist in all the chambers 2, 6, 13 and 15 and 15 the diaphragms will, therefore, all be balanced. The restricted orifice between the chambers 15 and 6 may be provided for in various ways without departing from the invention. It is herein shown at 17 and is 20 formed in a disk 18 that is secured by a cap 61 to the upper end of a stem 19 rising from the diaphragm 16, said stem having a duct 20 extending therethrough, and communicating at its lower end with the chamber 6. 25 The pilot valve 8 is connected to the diaphragm 16 through the medium of a yoke 21.

It will be remembered that under normal conditions the system pressure will exist in 30 the four chambers 2, 6, 13 and 15 and hence all three diaphragms will normally be in a balanced condition.

Spring means are provided for acting on the valves 5 and 8 and normally holding 35 them to their seats. In the present embodiment of the invention this spring means is in the form of a spring 23 which is situated between the valve 8 and a collar 24 that is fast on the valve stem 10. The single spring 40 23 thus functions to hold both valves to their seats.

The operation of the device is as follows. Under normal conditions the valves 5 and 45 8 will be retained closed as shown in Fig. 2 and the pressure in the four chambers 15, 6, 2 and 13 will be the same as that in the system. When a sprinkler head gives way the pressure will immediately fall in the system causing a corresponding decrease 50 of pressure in the chambers 2, 6, the pressure in the chamber 6 following that in the chamber 2 because of the size of the communicating duct 11. The restricted orifice 17, however, prevents any sudden drop of pressure 55 in the chambers 13 and 15 and as a result as soon as the sprinkler head opens and the pressure in the chambers 2 and 6 fall the diaphragm 16 will immediately become unbalanced and the preponderance of pressure 60 in the chamber 15 will tend to open the valve 8. The parts are so designed and arranged that the pilot valve 8 will open with a very slight decrease of pressure in the system.

As soon as this pilot valve is opened the air 65 in the pilot valve chamber 6 is immediately

exhausted through the port 7. The air in the chamber 2 will also escape into the chamber 6 through the duct 11 but since the duct 11 is very much smaller than the port 7 the pressure in the chamber 2 will fall much slower 70 than in the chamber 6. As soon as the pressure falls in the chamber 6 there will be a leakage of air from the chambers 15 and 13 into the chamber 6 through the restricted port 17 but because of the restriction of the port 17 the pressure change in the chambers 15 and 13 will be exceedingly slow.

As a result of the exhausting of the pilot valve chamber 6 in the manner above set forth the diaphragm 9 will become unbalanced and the preponderance of pressure in the chamber 13 will operate through the diaphragm 12 and the yoke 22 to lift the main valve 5 from its seat thus allowing a quick 85 exhaust of the chamber 2.

The port 4 is a large port and if it leads directly to the atmosphere the opening of the valve 5 will result in exhausting the air rapidly from the system thus quickly reducing the pressure on the air valve of the dry pipe 90 valve to the tripping point. On the other hand, if the exhaust port 4 leads to the neutral chamber of the dry pipe valve the result will be that the pressure in the system will be quickly introduced into said neutral 95 chamber thus neutralizing the air pressure against the air valve and causing the valve to trip.

The use of the pilot valve increases the 100 sensitiveness of the device and renders it quicker in operation.

In Fig. 3 I have shown an embodiment of the invention wherein the accelerating device is built into a dry pipe valve and in which it operates as an accelerator purely. In 105 Fig. 3 the dry pipe valve casing is shown generally at 25, it having the inlet 26 and the outlet 27 leading to the system. The inlet is normally closed by the water valve 28 which is connected to the air valve indicated generally at 29, the latter seating on the air valve seat 30 all as usual in dry pipe valves, there being the usual neutral chamber 33 between the valves. In this embodiment the air valve is provided with an extension 31 having a duct 32 therethrough which communicates at one end with the neutral chamber 33 and the other end of which is adapted to communicate with the system through the air chamber 33 of the dry pipe 110 valve. This extension 31 terminates in a valve seat 34 which is normally closed by a main valve 35 which is carried by a casing 36 that is secured to the dry pipe valve casing. This casing 36 carries at one end a diaphragm 37 to which the valve 35 is secured, said valve having a valve stem 38 which is 115 slidable through a bridge member 39 extending across the casing and which is acted on by a spring 40 that tends normally to 120 125 130

hold the valve seated against the valve seat 34.

The casing 36 is provided with an exhaust port 41 which is normally closed by a pilot valve 42 that is situated within the chamber 43 of the casing and which constitutes a pilot valve chamber. Said chamber 43 communicates with the system through a port 44 which leads through the wall of the casing into the recess 45 of the dry pipe valve casing into which the pilot valve casing is inserted.

The pilot valve is connected by a yoke 46 to a diaphragm 47 which extends across the casing 36 and separates the pilot valve chamber 43 from a pressure chamber 48. This pressure chamber 48 has a restricted communication with the system through a pipe connection 49 that has a disk 50 therein provided with a restricted orifice 51.

52 indicates a spring which acts against the diaphragm 47 and tends normally to hold the pilot valve seated. In this embodiment also under normal operating conditions the pressure in the system will exist in the air chamber 53 of the dry pipe valve, in the pilot valve chamber 43 and in the pressure chamber 48 and, therefore, the diaphragms 37 and 47 will be balanced.

50 The main valve 35 and the pilot valve 42 are held to their seats as shown in full lines by the springs 40 and 52. As soon as a sprinkler head gives way and the pressure in the system begins to fall there will be a corresponding fall of pressure in the air chamber 53 and the pilot valve chamber 43 but owing to the restricted orifice 51 the pressure in the pressure chamber 48 will decrease very slowly. Consequently, the diaphragm 47 will be immediately unbalanced thus opening the pilot valve 42 and allowing the air in the pilot valve chamber 43 to be rapidly discharged.

45 The exhaust port 41 for the pilot valve chamber is considerably larger than the port 44 and thus the air will exhaust from the pilot valve chamber 43 much faster than it can be admitted through the port 44. Consequently the diaphragm 37 will be unbalanced with the result that the preponderance 50 of pressure on the valve side of the diaphragm will force it back and thus open the main valve 35, as shown by dotted line position Fig. 3. The opening of the main valve 55 allows the air in the air chamber 53 and from the system to be delivered to the neutral chamber 33 with the result that the air pressure against the air valve will be neutralized thus causing the dry pipe valve to trip. 60 In this embodiment also the use of the pilot valve makes the device more sensitive and speeds up its operation, because by means of this construction a very small decrease of pressure in the system will be sufficient to 65 unseat the pilot valve. In both embodiments

of the invention also the pilot valve will operate only when the pressure in the system has a relatively rapid fall in pressure such as would result in the giving way of a sprinkler head. Any very slow change of 70 pressure in the system such as would result from a leakage less than the volume or amount which can pass through the restricted opening 17 or 51 will not effect the device because under such conditions normal 75 pressures will be maintained in the various chambers.

I claim:

1. In a device for accelerating the action of a dry pipe valve in a sprinkler system, 80 the combination with two chambers separated by a movable partition and each having a discharge port, of a valve normally closing each port, said chambers both communicating with the system, whereby normally both sides of the movable partition are subjected to the system pressure, one of the valves being secured to said movable partition, and means to unseat the other valve when the system pressure falls relatively rapidly and thereby unbalances the pressures on opposite sides of the movable partition, the first-named valve being unseated by the consequent movement of the partition. 85

2. In a device of the class described, the 90 combination with two chambers separated by a movable partition and each having a discharge port, a pressure chamber separated from one of said chambers by a second movable partition, the first two chambers having 100 a relatively free communication with the system and the pressure chamber having a restricted communication with said system whereby normally the system pressure obtains in all three chambers, a discharge valve 105 for one discharge port carried by the first-named movable partition, and a pilot valve for the other discharge port carried by the second-named partition, whereby when the system pressure falls relatively rapidly the 110 second-named movable partition will become unbalanced and will open the pilot valve thereby unbalancing the first-named partition and opening the other discharge valve.

3. In a device of the class described, the 115 combination with two chambers separated by a movable partition, one of said chambers having a main discharge port leading therefrom and having free communication with the system, and the other having a pilot 120 discharge port leading therefrom and having a partially restricted communication with the system, a main discharge valve normally closing the main discharge port, a pilot discharge valve normally closing 125 the pilot discharge port, whereby normally the system pressure obtains in both chambers, and means to unseat the pilot discharge valve upon a relatively rapid reduction of pressure in the system thereby accelerating 130

the reduction of the air pressure in the chamber having partially restricted communication with the system and quickly unbalancing the pressures on the movable partition thus causing the main discharge valve to be unseated.

4. In a device of the class described, the combination with two chambers separated by a movable partition, one of said chambers having a main discharge port leading therefrom and having free communication with the system, and the other having a pilot discharge port leading therefrom and having a partially restricted communication with the system, a main discharge valve normally closing the main discharge port, a pilot discharge valve normally closing the pilot discharge port, whereby normally the system pressure obtains in both chambers, means rendered operative by a relatively rapid fall of pressure in the system but not effected by a slow fall of pressure to open the pilot discharge valve, thereby to unbalance the pressure on the movable partition and cause the main discharge valve to be opened.

5. In a device of the class described, the combination with two chambers separated by a movable partition, one of said chambers having a main discharge port and having free communication with the system and the other chamber having a pilot discharge port and having a partially restricted communication with the system, a pressure chamber having a restricted communication with the system and separated by a movable partition with the chamber having the pilot discharge port, a main discharge valve normally closing the main discharge port and connected to the first-named movable partition, a pilot discharge valve normally closing the pilot discharge port and connected to the second-named movable partition, whereby both movable partitions are normally balanced and when the pressure in the system falls relatively rapidly the second-named movable partition will become unbalanced thereby opening the pilot valve which will in turn unbalance the other movable partition and open the main discharge valve.

6. In an accelerator for dry pipe valves, the combination with a dry pipe valve having an air valve, a water valve, a neutral chamber between said valves, an air chamber on the system side of the air valve and a passageway leading from the air chamber to the neutral chamber, of a pilot valve

chamber communicating with the system and having a discharge port, a pilot valve normally closing said discharge port, a diaphragm dividing said pilot valve chamber from the air chamber, a valve carried by said diaphragm for normally closing said passage, and means for causing the pilot valve to open upon the occurrence of a relatively rapid fall of pressure in the system, whereby the pilot valve chamber is exhausted and the diaphragm is moved to open said passage and allow system pressure to enter the neutral chamber.

7. In an accelerator for dry pipe valves, the combination with a dry pipe valve casting, an air valve and a water valve therein, there being a neutral chamber between said valves and an air chamber on the system side of the air valve and also a passage from the air chamber to the neutral chamber, of an accelerator casing carried by the dry pipe valve casting and having a pilot valve chamber communicating with the system and also provided with a discharge port, a movable partition subjected on one side to the pressure in the system and on the other to that of the pilot valve chamber, a valve carried by said movable partition and normally closing said passage, a pilot valve normally closing the discharge port of the pilot valve chamber, and means to unseat the pilot valve upon a relatively rapid fall of pressure in the system.

8. In an accelerator for dry pipe valves, the combination with a dry pipe valve having an air valve, a water valve and a neutral chamber between said valves, said air valve having a passage therethrough leading to the neutral chamber, of a pilot valve chamber communicating with the system and having a discharge port, a pilot valve normally closing said port, means to open the pilot valve when the pressure in the system falls due to the opening of a sprinkler head, a diaphragm subjected at one side to the system pressure and on the other side to the pressure in the pilot valve chamber, and a valve connected to the diaphragm and normally closing the passage through the air valve, whereby when the pilot valve is opened the pressures on the diaphragm will be unbalanced and the passage through the air valve will be opened.

In testimony whereof, I have signed my name to this specification.

EZRA E. CLARK.
